UNITED STATES PATENT OFFICE.

WARREN M. BRINKERHOFF, OF AUBURN, NEW YORK.

DESIGN FOR A PICTURE-HANGER.

SPECIFICATION forming part of Design No. 17,704, dated September 13, 1887.

Application filed August 12, 1887. Serial No. 246,811. Term of patent 14 years.

To all whom it may concern:

Be it known that I, WARREN M. BRINKERHOFF, a citizen of the United States, residing at Auburn, in the county of Cayuga and State 5 of New York, have invented and produced a new and original Design for Picture Hooks or Hangers; and I do declare the following to be a full, clear, and exact description of the same, reference being had to the accompanying 10 drawings, forming a part thereof.

My invention is a new design for picture-hangers, and is illustrated in the accompanying drawings, and is fully disclosed in the following specification and claims.

15 Figure 1 is a perspective view of my hanger provided with a plain surface. Fig. 2 is a like view of a hanger finished with ornamental figures thereon. Fig. 3 is a like view of a modification of the design shown in Fig. 2.

20 In my design I employ two vertically-disposed parts, A A, each provided at its upper end with a rearwardly-curving portion, forming a hook. These parts, at or near their lower ends, have a bar or strip, B, extending from one 25 to the other. This bar or strip is plain, as shown in Fig. 1, or it may have ornamental figures thereon, as shown in Fig. 2. Such figures may be on an additional plate or plates or strips attached to the hanger, as shown in Fig. 30 3. The figured design may be of any pre-

ferred pattern, and the vertical parts A A and their curved portions may be ornamented in the same manner as the bar or strip, or in a different manner when desired. The hanger is provided with a suitably-located projection 35 or projections, as at a a.

What I claim, and desire to secure by Letters Patent, is—

1. The design for a picture-hanger, consisting of two vertically-disposed parts having 40 rearwardly-extending curved portions at their upper ends and a bar or strip extending from one to the other at or near their lower ends, said parts being provided with a projection or projections, substantially as shown. 45

2. The design for a picture-hanger, consisting of two vertically-disposed parts, each provided at its upper end with a rearwardly-curved portion, and at or near their lower ends having a bar or strip extending from one to 50 the other, said bar being provided with an ornamental figured surface, the said hanger being provided with a projection or projections, substantially as shown.

In testimony whereof I affix my signature in 55 presence of two witnesses.

WARREN M. BRINKERHOFF.
